CLAIM

The ornamental design for gloves, as shown and described.

DESCRIPTION

FIG. 1 is an elevational palm-side view of a left hand glove according to the present invention;

FIG. 2 is an elevational backhand view of the glove of FIG. 1 according to the present invention;

FIG. 3 is a perspective view of the glove of FIG. 1 according to the present invention;

FIG. 4 is a perspective view of the glove of FIG. 1 according to the present invention;

FIG. 5 is an elevational palm-side view of the glove of FIGS. 1-4, shown with an unclaimed wearer;

FIG. 6 is an elevational backhand view of the glove of FIGS. 1-5, shown with an unclaimed wearer;

FIG. 7 is an elevational palm-side view of a right hand glove according to the present invention;

FIG. 8 is an elevational backhand view of the glove of FIG. 7 according to the present invention;

FIG. 9 is a perspective view of the glove of FIG. 7 according to the present invention;

FIG. 10 is a perspective view of the glove of FIG. 7 according to the present invention;

FIG. 11 is an elevational palm-side view of the glove of FIGS. 7-10, shown with an unclaimed wearer; and,

FIG. 12 is an elevational backhand view of the glove of FIGS. 7-11, shown with an unclaimed wearer.

FIGS. 3-6 and 9-12 show the design for the gloves in alternate positions for illustration purposes only.

The broken lines showing the gloves in use are included for the purpose of illustration and form no part of the claimed design.
